UNITED STATES PATENT OFFICE.

WALTER DUNKERLY, OF PROVIDENCE, RHODE ISLAND.

FAN ATTACHMENT FOR ROCKING FURNITURE.

SPECIFICATION forming part of Letters Patent No. 326,727, dated September 22, 1885.

Application filed May 2, 1885. (No model.)

To all whom it may concern:

Be it known that I, WALTER DUNKERLY, of Providence, in the State of Rhode Island, have invented an Improvement in Automatic 5 Fan Attachments for Rocking Furniture, of which the following is a specification.

My invention consists in the combination of a rocking chair or cradle with a weighted flexible fan and its attachments, as hereinafter 10 fully set forth.

Figure 1 is a perspective view of a rocking-chair with my improved automatic fan attached thereto. Fig. 2 is a perspective view of the metallic fastening, by means of which 15 the fan is secured to the chair. Fig. 3 is a plan view of the screw-stirrup of the fastening. Fig. 4 is a detail view of the lower portion of the fan, illustrating the preferred attachment of the fan-controlling weight-bar to 20 the lower edge of the fan. Fig. 5 shows an edge view of the fan when the lower edge of the same is loosely attached to the weight-bar.

In the accompanying drawings, A is a rocking-chair. B B are curved wire standards for supporting the flexible fan-sheet C, which is secured to the cross-bar D, connecting the upper ends of the standards B B. The fan-sheet C is to be made of any desirable flexible 30 material, (cloth or paper being very suitable for this purpose,) and is provided at its lower end with an attached bar-weight, E, which serves to impart the proper forcible vibratory movement to the fan-sheet in harmonious relation to the rocking movement of the chair or other article of rocking furniture to which 35 the fan may be attached.

In adapting the bar-weight E to the flexible fan-sheet C, and attaching the same thereto, I 40 prefer to bend or indent the bar, as shown at a a in Fig. 4, the distance between the bends a a being somewhat less than the width of the lower edge, o, of the flexible fan-sheet C, so that the lower portion of the sheet when the 45 corners m m are secured to the bar, as shown, will slightly bag under the opposing resistance of the air, thus serving to direct the air inward and downward at each vibration of the fan. The alternate inward curving of the 50 loose lower portion of the fan-sheet, resulting

from the described contracted attachment of the corners m m to the weight-bar, serves to prevent the air from escaping outward at the vertical edges n n when the fan is in rapid vibratory action, and is an important feature in 55 my invention, although highly-desirable results may be secured when the flexible fan-sheet C is secured to the bar E in an out-stretched condition.

In order to secure the standards B B to the 60 chair, I provide a metallic-fastening attachment, F, which consists of the fastening-plate e, provided with the slots d and e, which are adapted to receive the wire stirrup f, having at one end a head, g, and at the other end a 65 screw-thread and nut, h. The perforated enlargement i at one end of the plate e is adapted to receive the wire standard B, which is secured therein by means of the screw j, or otherwise.

In attaching my improved automatic fan to a rocking cradle the standards, which serve to support the bar D, to which the weighted flexible fan-sheet C is attached, may be secured either to the side or head of the cradle, 75 and the proper rocking movement of the same will impart a corresponding vibratory movement to the weighted flexible fan, which will serve to impart rapid motion to a refreshing downwardly-directed current of air.

I claim as my invention—

1. The combination, with a rocking article of furniture, of the flexible automatic fan secured to the said article of furniture and having its upper end outspread, while at its lower end the corners of the fan are brought nearer together and a bar-weight secured to the corners of the loose lower edge of the fan, substantially as described.

2. The combination of the weighted flexible fan C, the standards B B, attaching-plates e, provided with the slots d and e, and the perforated enlargement i, adapted to hold the standard B, and the screw-strap f, adapted to enter the slots of the plate e, substantially as 95 described.

WALTER DUNKERLY.
